CENTRIFUGAL PUMP

Carl Blom, San Marino, Calif., assignor to Byron Jackson Co., Huntington Park, Calif., a corporation of Delaware

Application June 13, 1941, Serial No. 397,836

2 Claims. (Cl. 103—109)

This invention relates generally to centrifugal pumps, and particularly to medium-pressure single case pumps of the type usually employed for pumping various classes of liquids in industrial processes.

A principal object of the invention is to simplify the construction of a pump of the foregoing type in order to reduce the cost of manufacture and to facilitate dismantling and re-assembly of the pump at the installation point.

A further object is to provide a pump of the foregoing type which is particularly adapted to handle liquids at high temperature. It is of utmost importance that adequate provision be made in pumps intended for this service to insure against differential expansion between parts at those critical points where surfaces contact to maintain centering or alignment between separable parts of the pump. Otherwise the centering or aligning surfaces may separate as the result of differential expansion, and may result in objectionable vibration of the inadequately supported part. It is an object of this invention to prevent such differential expansion by subjecting all mating portions of the pump to corresponding heating or cooling influences.

A still further object is to provide an improved impeller shaft bearing assembly which, in conjunction with the novel construction of the pump, simplifies the assembling and dismantling of the pump for inspection or repair.

A still further object is to provide a novel and improved lubrication system for the impeller shaft bearings.

The manner in which the foregoing and other objects are attained will be apparent from the following detailed description of one embodiment of the invention and a modification thereof, reference being had to the accompanying drawings wherein:

Fig. 1 is a longitudinal vertical sectional view of a pump embodying the invention;

Fig. 2 is a horizontal section taken on line II—II of Fig. 1;

Figs. 3, 4 and 5 are transverse sectional views taken on lines III—III, IV—IV, and V—V, respectively, of Fig. 1; and

Fig. 6 is a longitudinal vertical sectional view of a modification.

Referring to the embodiment shown in Figs. 1 to 5, there is shown a two-stage centrifugal pump having a pump casing 10. The casing 10 is preferably an integral casting having laterally extending bolting flanges 11 for attachment to pedestal 12 or other suitable supporting means. It will be observed that the opposite ends of the casing are provided with identical annular bolting flanges 13 and 14. A stuffingbox bracket 15 is secured to the flange 13, and an end cover 16 is similarly secured to the opposite flange 14 to complete the enclosure of the impeller spaces in the casing. A bearing bracket 17 is bolted or otherwise secured to the outer face of the stuffingbox bracket 15, and, if desired, may be additionally supported on the pump base by an auxiliary pedestal 17^a detachably secured to the bracket and to the base. The bracket 17 serves to rotatably support an impeller shaft 18 extending through the two brackets 17 and 15 and into the casing 10. A pair of impellers 19 and 20 are keyed to the inner end of the shaft, and are secured thereon by a nut 21 threaded on the end of the shaft.

Attention is directed particularly to the novel arrangement of fluid passages in the pump casing 10, which greatly simplifies the assembly and dismantling of the pump. It will be observed that the suction eyes of the impellers 19 and 20 face each other, thus disposing the corresponding suction passages in the casing in the central portion thereof between the impellers. A suction inlet passage 23 extends from the suction nozzle 24 to the eye of the first stage impeller 19, and is separated from the second-stage inlet passage 25 by a partition 26 having a wear ring 27 forming a throttle bearing with a sleeve 28 keyed to the shaft between the impeller hubs.

As shown most clearly in Figs. 4 and 5, the pump is of the double volute type, each impeller discharging into a pair of diametrically opposed volute passages in the pump casing. In this manner the radially acting hydraulic thrusts are balanced, and the impeller shaft is relieved of the bending stress which would otherwise be imposed thereon if a single volute were provided. Referring particularly to Fig. 4, diametrically opposed volute passages 30 and 31 are formed in the pump casing in the radial plane of the first-stage impeller 19. These passages are connected to the second-stage inlet 25 by individual cross-over passages 32 and 33 (Fig. 2) extending from the respective volute passages 30 and 31 in a generally axial direction on opposite sides of the suction inlet passage 23. After passing the inlet passage 23, the cross-overs 32 and 33 are curved radially inwardly and merge into the second-stage inlet 25. It will be observed from Figs. 2 and 4 that the suction inlet passage 23 is necessarily of very substantial width in a radial direction, and the

50 55

provision of individual cross-overs extending from the respective volute passages and around opposite sides of the large inlet passage affords a very compact and symmetrical construction.

The arrangement of the discharge volutes for the second stage impeller 20 is shown in Fig. 5. The volutes 35 and 36 start at diametrically opposite points on the circumference of the impeller opening in the casing, the volute 35 extending completely around the impeller and being separated from the volute 36 by a partition 37, which terminates near the upper end of the discharge nozzle 38.

Referring once more to Figs. 1 and 2, the shaft opening through the stuffingbox bracket 15 is sealed by a packing gland 41 of usual construction. In order to prevent undue heating of the packing when the pump is used to pump hot liquids, the stuffingbox is surrounded by a cooling jacket 42 to permit circulation of water or other cooling medium between an inlet (not shown) and an outlet 43. As is customary, provision is also made for circulation of water through the stuffingbox from an inlet connection 44 to a lantern ring 45 and thence between the packing 41 and a shaft sleeve 46 to an outlet 47 in the packing follower.

It will be noted that the pump casing 10 is provided with a cylindrical centering surface 50 adjacent the bolting flange 13, and that the stuffingbox bracket 15 is provided with a corresponding centering surface 51 adapted to have a close sliding fit in the centering surface 50 to insure axial alignment of the bracket with the pump casing. It is essential that these surfaces 50 and 51 be maintained in contact with each other in order to avoid vibration of the bracket. It has been found, however, that these surfaces frequently become separated as the result of differential expansion between the casing and the bracket when pumping hot liquid. The pump casing, being exposed to the hot pump liquid, may be heated to a higher temperature than the stuffingbox bracket, inasmuch as the latter is subjected to the cooling influence of the cooling water in the jacket 42.

In order to avoid separation of the centering surfaces 50 and 51, I have provided an arrangement whereby the portion of the stuffingbox bracket 15 in the region of the centering surface 51 is subjected to the heating influence of the pump liquid, to thereby cause it to expand or contract with the pump casing. To this end, the inner radially extending wall of the bracket 15 is recessed into the water jacket 42, as indicated at 55, to provide an annular pocket or channel 56 which contains pump liquid when the pump is in operation. The annular flange 57 thus formed between the pocket 56 and the centering surface 51 is thereby isolated from the cooling effect of the cooling liquid in the jacket 42 and is exposed directly to the pump liquid, and will be heated to approximately the same temperature as the portion of the casing 10 on which the centering surface 50 is formed. In this manner, differential expansion between the pump casing and the bracket in the region of the centering surfaces 50 and 51 is avoided, and vibration of the bracket resulting from separation of the surfaces 50 and 51 is consequently eliminated.

Referring now to the bearing bracket 17 and the mounting of the impeller shaft 18 therein, it will be observed with reference to Figs. 1 to 3 that the bracket comprises an inner circumferential wall 60 forming with the end covers 61

and 62 a completely closed bearing housing, and an outer wall 63 spaced from the wall 60 to form therewith a cooling jacket 64. Cooling liquid is circulated through the jacket between an inlet 5 and an outlet 66. A deflector ring 61a is secured to the shaft adjacent the end cover 61 to prevent cooling liquid issuing from the stuffingbox from entering the bearing housing.

The shaft 18 is journaled in the bracket 17 in 10 spaced bearings 67 and 68, preferably of the ball bearing type. The bearing 67 assumes only radial thrust, being mounted for limited sliding movement in the bearing seat 69 in the bracket. The bearing 68 assumes not only radial load but 15 also any axial hydraulic thrust imposed on the shaft by the impellers. To this end, the outer race of the bearing 68 is provided with a circumferential groove containing a split retaining ring 70 adapted to be clamped between the end 20 wall of the bracket and the end cover 62. The inner race of the bearing 68 is secured to the shaft between a shoulder on the shaft and a nut threaded thereon. This construction has the 25 advantage of permitting the use of a standard bearing without requiring a counterbore in the bracket to form a seating shoulder for the outer race. The bore 71 in the bracket is only slightly larger than the inner bearing 67, to permit the latter to be inserted freely therethrough during 30 assembly.

I have provided a novel and improved system of lubrication of the bearings 67 and 68. The housing formed by the walls 60, 61 and 62 constitutes a lubricant reservoir having a filling 35 opening 75 through the upper wall and a drain port 76 in the sump formed in the lower portion. A supply of lubricant is maintained at approximately the level indicated at 77. An oil flinging disk 78 is secured to the shaft approximately 40 midway between the bearings, as by a set screw 79, and it will be noted that the flanges of the disk extend below the level of the lubricant. During rotation of the shaft, the lubricant adhering to the submerged portion of the disk 45 flanges is carried upwardly and flung outwardly by centrifugal force against the wall of the housing.

In order to collect the lubricant flung from the disk and to direct it to each bearing, a channel 50 80 (Fig. 3) is formed on the inner wall of the housing. As shown most clearly in Fig. 1, the channel slopes downwardly in opposite directions from the central radial plane of the disk 78. Ports 81 and 82 extend through the end walls of 55 the bracket in registry with the respective ends of the channel 80, to direct the lubricant from the channel to chambers 83 and 84 between the outer sides of the bearings and the end covers 61 and 62. From these chambers the lubricant 60 flows through the bearings and returns to the reservoir. A continuous circulation of oil through the bearings is thus provided. On the radially opposite side of the housing and approximately 65 at the same elevation as the ports 81 and 82, a pair of overflow ports 85 and 86 extend through the end walls of the housing to allow any excess lubricant to by-pass the bearings and thus control the level of the lubricant in the chambers 83 and 84.

The oil-flinging disk 78 is superior in several respects to the conventional oil rings now in common use. A ring loosely mounted on the shaft is not positively rotated by the shaft, and frequently such rings become worn in one spot and 75 fail to rotate. The disk 78, however, is rigidly

secured to the shaft and hence affords a positive means for throwing oil onto the housing where it drains into the channel 80. It will be noted that the disk 78 is slightly smaller than the bore 71 in the outer end wall of the housing, to permit insertion of the ring when mounted on the shaft.

From the foregoing description, it will be apparent that I have provided a pump which is exceedingly simple to assemble and dismantle, and which will provide trouble-free operation over a long period of time irrespective of the temperature of the liquid being pumped. The manner of assembly is believed to be obvious. It is desired to call attention, however, to the ease of dismantling to permit inspection of the rotating parts and the interior of the pump casing. Upon removal of the end cover 16, the impeller nut 21 is removed from the shaft, permitting the removal of the second stage impeller 20. After the stuffingbox bracket 15 has been unbolted from the flange 13 on the pump casing and the detachable pedestal 17^a has been removed, the entire unit comprising the stuffingbox bracket 15, bearing bracket 17, and the shaft 18 with the impeller 19 thereon may be withdrawn bodily to the right, thus affording access to the interior of the pump casing and permitting inspection of the impellers. It will be noted that inasmuch as the suction and discharge connections form a part of the pump casing, it is not necessary to disturb those connections in order to dismantle the pump.

If it is desired to inspect the bearings 67 and 68, this may be accomplished with only slight additional dismantling. The impeller 19 is removed from the left end of the shaft, the end cover 62 is unbolted from the bearing bracket 17, and the deflector ring 61^a is loosened, and thereafter the shaft 18, bearings 67 and 68, and oil-flinger ring 78 may be withdrawn to the right as a unit, leaving the brackets 15 and 17, packing gland 41, and shaft sleeve 47 intact. Separation of the bearing bracket from the stuffingbox bracket is, of course, necessary in order to renew the packing 41. It will be apparent from the foregoing that the pump is susceptible of being separated into various sub-assemblies to permit inspection of the various operating parts, but it is not necessary, however, to completely dismantle the pump in order to inspect and/or renew a single part.

Referring now to the form of the invention shown in Fig. 6, it will be observed that this form embodies many features and parts found in the pump which has been previously described. The principal distinction between the two embodiments lies in the fact that the pump shown in Figs. 1 to 5 is of the "overhang" type wherein the shaft and impellers are supported only at one side of the pump casing, whereas in Fig. 6 the shaft is supported in bearings at opposite ends of the pump casing.

The pump casing 110 of Fig. 6 is of identical construction with the casing 10 of Figs. 1 to 5, thus providing interchangeability of parts. The stuffingbox brackets 111 and 112, detachably secured to opposite ends of the pump casing, are also identical with each other and with the bracket 15 of Figs. 1 to 5. This is rendered possible by providing identical bolting flanges at opposite ends of the coupling, permitting the selective attachment of either two identical brackets as in Fig. 6 or of a bracket 15 and an end cover 16 as in Fig. 1.

Bearing brackets 115 and 116 of identical con-

struction are detachably secured to the outer ends of the respective stuffingbox brackets 111 and 112, and each houses and supports a shaft bearing. The bearing 117 in the bracket 115 is of the plain sleeve type and assumes only radial load from the shaft 118, whereas the bearing 118 in the bracket 116 assumes radial load and also absorbs any axial hydraulic thrust imposed on the shaft by the impellers. The latter bearing 118 is shown as a conventional stacked ball bearing.

It will be observed that the arrangement of the impellers with their suction eyes facing each other is the same in Fig. 6 as in Fig. 1, since the pump casings are identical. It will also be observed that the brackets 111 and 112 are provided with annular pockets or channels 120 and 121 to provide annular flanges 122 and 123 which are isolated from the cooling effect of the stuffingbox cooling water and are exposed to the pump liquid filling the pockets 120 and 121, to assure uniform expansion of the flanges with the adjacent portions of the pump casing when pumping hot liquid. Separation of the cylindrical centering surfaces 124 and 124' on the casing from the corresponding entering surfaces 125 and 125' on the brackets, and the consequent vibration of the brackets, are thereby avoided.

The assembly and dismantling of this pump is slightly more complicated than is the case with the pump of Figs. 1 to 5, but nevertheless involves a minimum of operations for this type of pump. In order to gain access to the impellers and to the interior of the pump casing, the bracket 111 is disconnected from the flange on the casing and is withdrawn bodily to the right with the bearing bracket 115 and its bearing 117. The shaft sleeve 130 and the first stage impeller 131 are then removed to the right, leaving the shaft free to be withdrawn to the left with the impeller 132 and the brackets 112 and 116.

It will be appreciated that certain aspects of the invention are equally applicable to other types of centrifugal pumps than the two which have been illustrated and described. For example, the novel construction whereby separation of the mating centering surfaces on the casing and the bracket is avoided, is equally applicable to other than two-stage pumps. The improved bearing construction and bearing lubrication system may also be used in conjunction with other types of pumps than those described. It will therefore be understood that the invention is not limited to the detailed construction shown in the accompanying drawings, but is of the full scope of the appended claims.

I claim:

1. In a multistage centrifugal pump, a unitary, circumferentially continuous pump casing having a removable closure at each end thereof and having a pair of axially spaced impeller cavities therein, an impeller shaft mounted in said casing, first and second stage impellers on said shaft and rotatable in said cavities and disposed with their suction eyes facing each other, said casing having a pair of juxtaposed inlet chambers located between the impeller cavities and communicating respectively with the suction eyes of the impellers, said casing having a partition separating said inlet chambers, said partition being formed integral with the casing and extending inwardly into close proximity to said shaft, a suction inlet passage in said casing communicating with the inlet chamber of the first stage impeller, a pair of

discharge volutes in said casing arranged on diametrically opposite sides of said first stage impeller, separate cross-overs leading from said volutes to the inlet chamber of the second stage impeller, said cross-overs extending in a generally axial direction past said suction inlet passage on opposite sides thereof, and discharge outlet passage means leading from the second-stage impeller.

2. A multistage centrifugal pump as set forth in claim 1 in which a common plane extending centrally through the axially extending portions of said cross-overs is substantially at right angles to the axis of said suction inlet passage.

CARL BLOM.
